UNITED STATES PATENT OFFICE.

AARON MENDELSON, OF NEW YORK, N. Y.

CIGARETTE-CASE.

1,160,933.

Specification of Letters Patent.

Patented Nov. 16, 1915.

Application filed October 23, 1914. Serial No. 868,212.

To all whom it may concern:

Be it known that I, AARON MENDELSON, a citizen of the United States, and a resident of the city of New York, borough of Brooklyn, in the county of Kings and State of New York, have invented a new and Improved Cigarette-Case, of which the following is a full, clear, and exact description.

This invention appertains to improvements in cigarette cases or like receptacles for holding elongated objects which, in order to insure their best keeping and permit their convenient withdrawal without resultant injury, must be held independently so as not to come in contact with each other or be permitted to move about when the receptacle is closed but to move in spaced relation and out of the sections forming the receptacle or case when the latter is open.

More particularly, the invention comprehends the provision of an improved cigarette case, the sections of which are hinged together and designed to spring to an open position or be opened by hand upon the release of a spring catch provided to hold the sections in closed relation, the cigarettes in the present instance being mounted in independent tubular holders pivotally supported upon a pivot diagonally arranged across the hinged ends of the sections and connected to opposed sections so as to operate as a spring tending to normally spread the sections apart, while the holders are so mounted as to cause them to assume a fan-like tortuous condition, crossing each other in divergent relation so that the cigarettes held therein are similarly disposed.

With the above and other objects in view, the invention resides more particularly in the peculiar combination and arrangement of parts to be hereinafter more fully described, illustrated and claimed, it being also an object to provide a device which is simple in construction, durable and efficient.

Reference is to be had to the accompanying drawings forming a part of this specification, in which similar characters of reference indicate corresponding parts in all the views, and in which—

Figure 1 is a perspective view of the improved cigarette case in an open position with cigarettes mounted in certain of the holders; Fig. 2 is a plan view thereof with certain of the holders omitted; Fig. 3 is a cross sectional view of the case in a closed

position; Fig. 4 is a fragmentary detail view showing in perspective elevation the manner of pivotally mounting the holders and causing them to move into spaced relation when the case is opened by springing the sections thereof apart; Fig. 5 is a detail perspective view of a fragmentary portion of one of the holders; and Fig. 6 is a detail sectional view taken on the line 6—6 of Fig. 1.

As illustrated, the improved cigarette case embodies a pair of sections 10 and 11 preferably provided with rounding corners as shown at 12 and having relatively thick but shallow rims 13 adapted to contact when the sections are brought together edgewise to a closed position. To permit this the sections are hinged together as by means of a pintle 14 engaging interacting pivot ears 15 of the sections in such a manner as to permit the sections to freely move on the pintle. The sections adjacent to the hinge connections are provided with shoulders 16 which are spaced apart when the sections are closed but which contact with each other to limit the opening movements of the sections of the case less than 180° to facilitate the handling thereof and subsequent closing of the sections. Shoulders 17 are also provided at the inside of the sections to limit the movements thereof to closed positions and take the jar incident to the closing together of the sections.

One of the sections, such as the section 11, is provided with inside corner flanges 18 inwardly of the rim 13 thereof so as to enter the other section and thereby serve as a guide to cause the sections to properly move together and the consequent locking thereof in closed position through the instrumentality of a spring catch 19 which engages a shouldered notch 20 centrally of the free edge of the opposing section and which is held in locking engagement therewith by a flat spring strip 21 secured inside of the section 11 and movably operating at its ends behind retainers 22 which also form guides for the extremity of the spring to prevent its displacement when the spring is depressed as by means of a button or projection 23 which operates through an opening in the edge of the section 11 under the action of the spring tending to normally assume a rectilinear condition.

Extending transversely of the box from side to side of the sections thereof, and preferably extending diagonally from the inner

corner of one section to the opposite corner of the other section, is a spring pivot 24, the same extending through apertured lugs 25 near each end of the spring pivot with one lug fixed to each section. In this manner this spring pivot must be bent or twisted slightly when the sections of the case are closed so that the pivot constitutes spring means to retain the sections of the case in open position, as shown in Figs. 1 and 2 of the drawings, limited by the shoulders 16 in the manner heretofore described.

In order to hold the cigarettes or like articles 26, a plurality of holders are provided, the same in the present instance being illustrated as tubular holders 27 of oval or elliptical cross section secured to pivot sleeves 28 loosely mounted on the spring pivot 24. As illustrated, these holders are provided with a series of longitudinal slots or openings 29 to lighten the structure and improve the design and at their extremities are beaded, as shown at 30, with the alternate holders shorter than the others so that the free ends thereof will terminate beneath the beaded portions of the adjacent holders or otherwise if desired. The sleeves 28 are so constructed and mounted on the spring pivot as to cause the holders and the cigarettes or other commodities held therein to move in spaced relation when the case is opened by springing the sections apart, and in the present instance each sleeve projects beyond diametrically opposite points of its holder and such projecting ends have portions thereof cut away as shown at 31, the degree of omission or removal of the end portions of the sleeves and the relative location of these cutaway portions to the holders being such that while their end portions come closely adjacent to each other so that the reduced ends will be disposed in overlapped relation, the edge portions 32 will be slightly spaced apart as shown at 33 and arranged in a spiral line lengthwise of the spring pivot to constitute lost motion between the sleeves of the holders so that one holder will have slight play independent of the adjacent holders and will move a predetermined distance above the edge portions of its sleeve and will engage the edge portions of the adjacent sleeves to impart turning movement or rotation thereto on the spring pivot. In this manner the holders may be caused to assume the position shown in Fig. 1 of the drawings, with the holders spaced apart and crossing or intersecting each other partly so that the free ends thereof will diverge to dispose the cigarettes in similar relation. This action is effected by forming each end sleeve with a bifurcation 34 designed to straddle one of the lugs 25 which are rigid with the opposed sections, the sleeves and holders being thus limited against endwise movement or constrained to translate so that the extreme ends

of said sleeves at the extremities of the spring pivot need not be reduced or formed with shoulders but said sleeves or the holders thereof are anchored to the adjacent sections against movement in any suitable way 70 so that the end holders will move with the sections when the latter are sprung apart or moved together in closing the case. For this purpose the end holders may carry angular pieces 35 which may be soldered or 75 otherwise secured thereto adjacent to their sleeves and to extend beneath the flanged rims 13 in order to hold these end sleeves against pivotal movement or substantially so. 80

It will thus be seen that when the case is in a closed position and the catch is released the spring pivot 24 will immediately spread the sections apart to open the case, while one section is held in the hand, or if the sections are spread apart, due to the fact that the end holders are anchored thereto, the holders will be successively moved into spaced relation as the shoulders or edge portions 33 of the sleeves 28 come in contact and due to the spaces between said shoulders the lost motion thus provided will permit the holders to move into spaced relation. Furthermore, since the holders are spirally arranged on the spring pivot and the latter 95 is diagonally disposed across the adjoining ends of the sections, the holders will be caused to assume a fan-like or sinuous condition, although the essential fact is that the holders are disposed in spaced relation 100 to permit the convenient withdrawal of the cigarettes or commodities held therein. Upon the case being closed against the action of the spring pivot the lost motion provided will, after certain of the edges of the sleeves which have been brought together in causing the holders to move in the relation specified, allow the other edges which have been thereby moved into spaced 110 relation to come together with the holders 110 substantially in alinement inclosed in the opposed sections, as shown in Fig. 3.

Having thus described my invention, what I claim as new and desire to secure by Letters Patent is:—

1. The combination of a normally straight support, means for bending the support, a plurality of article holders pivotally mounted on the support, and interengaging means between the holders for supporting the same in divergent relation when the support is bent.

2. The combination of a resilient wire normally straight, means connected with the wire for imparting a bend thereto, a plurality of holders mounted to swing on the wire, means for imparting movement to the outermost holders, and interengaging means between adjacent holders to form lost motion connections whereby one holder im- 125 130

parts movement to the next as the wire changes from a straight condition.

3. The combination of a container having hingedly connected sections, a resilient support having one end connected with one section and the opposite end connected with the other section and adapted to extend across the hinge between the sections when the latter are moved to open position, and
- 5 10 a plurality of article containers mounted on the support and automatically thrown to diverging position as the sections of the container are moved open.

4. The combination of a container having hingedly connected sections, a resilient support having one end connected with one section and the opposite end connected with the other section and adapted to extend across the hinge between the sections when
- 15 20 the latter are moved to open position, a plurality of article containers mounted on the support and automatically thrown to diverging position as the sections of the container are moved open, and lost motion connections between adjacent holders.

5. A box comprising hingedly connected sections, a wire having its opposite ends connected with the respective sections adjacent the hinge between the latter, and said wire being normally straight when the box is closed, and adapted to bend as the box opens, a plurality of article holders pivotally mounted on the wire and normally disposed parallel when the wire is straight,
- 30 35 means connecting the outermost holders with the respective sections of the box, and lost motion connections between adjacent holders, whereby one holder in moving imparts a lost movement to an adjacent holder.

- 40 45 50 6. A cigarette case comprising hinged sections, means to hold said sections in closed position, a pivot arranged to be inclosed therein and holders having sleeve portions mounted on the pivot, said sleeve portions being independently mounted and a lost motion connection between adjacent sleeve portions, whereby as the box sections are spread apart the holders will be successively actuated to move in spaced relation to adjacent holders.

7. A cigarette case comprising hinged sections, means to hold said sections in closed position, a pivot arranged to be inclosed therein, holders having sleeve portions mounted on the pivot, said sleeve portions being independently mounted and a lost motion connection between adjacent sleeve portions, whereby as the box sections are spread apart the holders will be successively actuated to move in spaced relation to adjacent holders and means to limit endwise displacement of the holders.

8. A cigarette case comprising hinged sections, means to hold said sections in closed position, a pivot arranged to be inclosed

therein, holders having sleeve portions mounted on the pivot, said sleeve portions being independently mounted with lost motion between the same, whereby as the box sections are spread apart the holders will be

70 75 successively actuated to move in spaced relation to adjacent holders, said pivot extending diagonally at the hinge joint of the sections to cause the holders to assume a tortuous fan-like relation and means carried by opposed sections and engaged with the end sleeves to prevent endwise displacement thereof.

9. A cigarette case comprising a pair of sections hinged together, a spring catch for holding said sections in closed position at their free edges, means to limit the opening and closing movement of the sections, a spring pivot connected at its ends to opposed inner corners of said sections and extending across the hinge, independent tubular holders and means pivotally mounting said holders independently on the spring pivot to cause the same to successively move into spaced relation across the case when the sections are swung open upon the release of the catch.

10. A cigarette case comprising a pair of sections hinged together, a spring catch for holding said sections in closed position at their free edges, means to limit the opening and closing movement of the sections, a spring pivot connected at its ends to opposed inner corners of said sections and extending across the hinge, independent tubular holders, a sleeve carried by each holder, each sleeve having reduced end portions projecting beyond the sides of the sleeves to dispose the latter in spaced relation transversely of the case, said sleeves being loosely mounted on the spring pivot, lugs engaged with the end sleeves to retain all of said sleeves on the spring pivot, the joints of said sleeves being loosely engaged on the spring pivot with intermediate spaces constituting lost motion and means anchoring the end holders substantially against movement with respect to the opposed sections, whereby the separation of the sections will result in successive motion being imparted to the intermediate sleeves to move the same into spaced divergent relation.

11. A cigarette case comprising two hingedly connected sections, a pivot having one end connected with one section and the opposite end connected with the other section and extending across the hinge, and cigarette holders having sleeves at their lower ends, the sleeves of various holders being arranged in alinement and through which the said pivot extends, whereby the holders are mounted in the case.

12. A cigarette case comprising two hingedly connected sections, a wire having its ends connected with the respective sections

at opposite ends of the case, and cigarette holders individually loosely mounted on the wire, and lost motion connections between adjacent holders.

5 13. A cigarette case comprising hingedly connected sections, a wire disposed in the case to form a pivot, cigarette holders, a sleeve fastened to the bottom end of each holder and extending diametrically across 10 the same, the sleeves of the holders being arranged in alinement and the wire extending through the sleeves for pivotally mounting the holders in the case, and means for automatically throwing the holders out of 15 the normal plane they occupy when the case is closed for separating the adjacent upper

ends of the cigarettes when the case is opened.

14. A cigarette case comprising hingedly connected sections, a wire fastened only at 20 opposite ends to the respective sections, sleeves arranged in end to end relation and loosely mounted on the wire, and a cigarette holder rigidly fastened to each sleeve.

In testimony whereof I have signed my 25 name to this specification in the presence of two subscribing witnesses.

AARON MENDELSON.
